United States Patent Office.

ANDREW O'NEILL, OF PORTSMOUTH, OHIO.

Letters Patent No. 80,995, dated August 11, 1868.

IMPROVEMENT IN WASH-BOILERS.

The Schedule referred to in these Letters Patent and making part of the same.

TO ALL WHOM IT MAY CONCERN:

Be it known that I, ANDREW O'NEILL, of Portsmouth, in the county of Scioto, and State of Ohio, have invented a new and useful Improvement in Wash-Boilers; and I do hereby declare that the following is a sufficiently full, clear, and exact description thereof, to enable one skilled in the art to which my said invention appertains, to make and use it, reference being had to the accompanying drawings, which are made a part of this specification.

The subject of my invention is a removable inner boiler, of peculiar construction, adapted to be placed within a common boiler, and when so placed, to induce an active and forcible circulation of water, under the action of heat. In the drawings—

Figure 1 is a central vertical section, representing my wash-boiler applied to a boiler made under my several patents of August 22, 1865, and February 20, 1866.

Figure 2 is a plan of the same partly in section.

Figure 3 represents a side elevation thereof, a portion of the outer boiler being removed to expose that to which my present invention relates.

Figure 4 is a vertical section, showing the invention applied to a common "agricultural kettle."

Similar letters of reference indicate corresponding parts in the several views.

A represents an outer boiler, which may be of any common or suitable construction. B is the inner boiler, to which my invention relates. The said inner boiler is separate and removable from the outer boiler A, but, while in position within the latter, is made to fit tightly by means of an elastic or compressible gasket, C, located at any proper height. Below the gasket C is a range of apertures, D, passing through the wall of the inner boiler B, and extending completely around the same. On the inside, the apertures D are surmounted by hoods E, presented radially toward the centre. F F F represent a second range of apertures, located near the bottom of the inner boiler. Deflectors G may be applied on the outside, under the apertures F, to prevent the hot water from beneath the inner boiler entering through the said apertures in its upward course.

In some cases, I also propose to use directing-plates H, on the outside of the inner boiler, to conduct the ascending water to the apertures D. I represents a straining-cloth, placed above the clothes to arrest any insoluble matter which may have been once removed therefrom.

The operation is as follows:

The outer boiler A is supplied with water, and the clothes to be washed are placed in the inner boiler B. The water in the bottom of the outer boiler, as it becomes hot, will rise around the sides of the inner boiler, and being confined by the packing-gasket, will be forcibly driven in through the apertures D, on to the top of the clothes or on to the straining-cloth I above them. Hot water is thus constantly applied to and forced through the clothes, and passing out through the lower apertures F, is as constantly reheated in the bottom of the outer boiler.

An inner boiler, B, constructed as above described, and provided with a gasket, C, may be placed within a common cast-iron kettle or boiler of almost any form, and by keeping the clothes from contact with the iron, prevents any danger of iron-moulding. I thus, at a trifling cost, provide means whereby a common boiler, which is ordinarily used for other purposes, may be converted at will into an automatic wash-boiler of the most efficient character.

The closure effected by the gasket C, compels the ascending water to enter the boiler B through the apertures D, and thus avoids the necessity of a cover over the whole.

When my inner boiler is applied to an outer boiler with straight sides, as illustrated in figs. 1, 2, and 3, the gasket will be received by a "swage" or rib, c, to support the inner boiler, with its bottom sufficiently above that of the outer boiler to leave the necessary water-space between them.

The upward convergence of the annular water-space between the two boilers, imparts greater velocity to the water as it rises, and causes it to be ejected through the apertures D with great force.

By having no perforations in the bottom of the inner boiler, I prevent the reflux of steam and water upward through the bottom, which, in automatic boilers heretofore constructed, causes great inconvenience by throwing up the clothes, and interfering with the desired circulation of water.

I do not claim as new, so constructing a wash-boiler, that water will be caused to circulate in it by the application of heat, as I am aware that this is done in the wash-boiler of M. W. Staples, for which Letters Patent were granted, February 12, 1867, and reissued, December 17, 1867, and in some others.

Having thus described my invention, I claim as new, and desire to secure by Letters Patent—

The removable inner boiler B, provided with a packing or gasket, C, and adapted for application to an outer boiler of common construction, to constitute an automatic wash-boiler, as explained.

ANDREW O'NEILL.
